UNITED STATES PATENT OFFICE.

HENRY LEITNER, OF LONDON, ENGLAND.

VARIABLE-SPEED DYNAMO.

1,094,077.

Specification of Letters Patent. Patented Apr. 21, 1914.

Application filed April 11, 1912. Serial No. 690,052.

To all whom it may concern:

Be it known that I, HENRY LEITNER, a subject of the King of Great Britain, residing at Westminster, London, England, have invented new and useful Improvements in Variable-Speed Dynamos, of which the following is a specification.

This invention relates to variable-speed dynamos of the kind commonly employed in connection with train lighting and for like purposes, and wherein one or more subsidiary brushes is or are used to control the field-magnet circuit for self-regulating purposes, one example of which is shown and described in my former U. S. Patent #863,410 dated August 10, 1907.

The present invention has for its object to provide increased efficiency in the action of the subsidiary brush or brushes as regards the self-regulating properties of dynamos of this type, whereby the output is maintained more constant both as to voltage and current. To this end according to my invention I reduce very considerably the extent of the polar arc, and, therefore, the arc of the resulting magnetic flux from the pole to the armature, and this I may accomplish by reducing, and in some cases by dispensing altogether with, the usual magnet pole-shoes, and by making the pole-cores or shanks of such a sectional shape as to constitute efficient poles; for example, I may make the pole-cores in cross section of an elliptical shape, or in the form of a truncated ellipse, or of a diamond or double-V shape, or of a truncated diamond shape.

To enable the invention to be fully understood, I will describe it by reference to the accompanying drawings, in which:—

Figure 1 is a semi-diagrammatic view, partly in section, of a bi-polar dynamo constructed according to the invention, in which two subsidiary brushes are employed in the field circuit. Fig. 2 is a view similar to Fig. 1 illustrating an arrangement in which only one subsidiary brush is employed in the field circuit. Fig. 3 is a view giving in cross section four alternative shapes of pole-pieces, and Figs. 4 and 5 are views showing some comparative output curves hereinafter explained.

a represents the armature of the dynamo, b the commutator thereof, c, c¹ the field-magnets and poles and d the body or yoke. e, e¹ are the main brushes which supply

current to the external circuit through the conductors f, f¹.

x, y is the normal center line or axis of the magnetic flux, and is coincident with the center line of the poles c, c¹.

In the arrangement illustrated in Fig. 1, two subsidiary brushes g, g¹ respectively are made use of, the said brushes being placed midway between the main brushes e, e¹ to which, together with the said subsidiary brushes, a certain amount of physical lead is given in the direction of rotation of the armature indicated by the arrow.

As above described the field-magnets and poles c, c¹ are made of a sectional shape such that they constitute efficient poles. In Fig. 3, I have shown four sections which will give good results in practice, the section h being of elliptical shape, the section i in the form of a truncated ellipse, the section j of a double-V or diamond shape and the section k of a truncated diamond shape. It will be understood, however, that other shapes may be made use of which give rise to the same result.

In machines constructed as above described a marked advantage is obtained both as regards output and self-regulating properties as compared with the more general design in which it is usual to employ pole-shoes and to make the polar arc about 70 per cent. of the pole-pitch or circular distance between the centers of the adjacent poles.

It is well understood that when a dynamo is loaded, the magnetic flux suffers distortion owing to armature reaction, and the axis of the flux which is normally, that is to say when the machine is not loaded, coincident with the center line of the poles, is displaced in the direction of rotation of the armature. The effect of limiting the extent of the polar arc, and of the resulting arc of the magnetic flux by the construction herein described is, in the first place, to limit or restrict the displacement of the axis of the magnetic flux within a narrower range, and, in the second place, and by reason of this limitation, to give to the subsidiary brush or brushes a virtually increased "lead" in the direction of rotation.

The amount of subsidiary current or subsidiary E. M. F. furnished by the subsidiary brush or brushes when connected between the principal brushes of the machine and

the shunt field-winding as shown in the accompanying drawings, depends on the angular distance or "lead," in the direction of rotation, from the line passing through the center of the pole-pieces, and by giving to the subsidiary brush or brushes a certain amount of physical "lead," the effect is obtained that when the machine commences to rotate and excites, the subsidiary brush or brushes assists or assist in building up the field, but this building up, or "boosting," effect is reduced to zero when the axis of the magnetic flux becomes coincident with the subsidiary brush or brushes, and may even have a negative value if the axis is displaced still further. With the present construction, therefore, in which the axis of the magnetic flux does not suffer so great a displacement, the E. M. F. of the subsidiary brush or brushes, having a certain amount of "lead," although still gradually diminishing proportionately with increase of load and speed, does not so soon, or does not at all, reach this zero value, that is to say, there is a virtually increased "lead" in the direction of rotation, and a continual though diminishing "boosting" effect. In addition to the diminished polar arc I may, therefore, give to the subsidiary brush or brushes a greater proportional physical "lead" relatively to the polar axis than that which is given to the main brushes, that is to say, for example, in a bi-polar machine, the subsidiary brush or brushes may not only be behind or on, but preferably in advance of, a line at right angles to the main brushes. Such an arrangement is illustrated in Fig. 2 where the dynamo is shown as being furnished with a single subsidiary brush g having the greater proportionate lead above referred to. As above stated, a dynamo constructed as described is characterized by an increased output, as compared with such machines as hitherto generally constructed. The extent to which the output of the machine is improved, is such that the much less permeable cast-iron may be made use of for the yoke and poles of the machine, and still a larger output be obtained than from a machine of the usual design and of the same size and having the more permeable cast-steel yoke and poles. Furthermore, I also obtain the advantage that the poles can be cast in one piece with the yoke.

Fig. 4 shows the output curves of two similar sized machines designed for train lighting purposes, the curve A representing the output of a machine constructed in accordance with my former United States patent hereinbefore referred to, and having cast-steel yoke and poles, while the curve B represents the output of a cast-iron machine of the same size constructed with the

reduced polar arc, and in which the output, though purposely restricted is still very considerably greater than that of A. The curve marked C is taken from the same machine, but with the subsidiary brushes having a greater lead, and it shows the enormously increased output which may be thus obtained. Any output or form of curve may thus be obtained with my improved construction of dynamo within the limits given by the rising curve C and the drooping curve B by the adjustment or variation of the lead of the subsidiary brush or brushes.

Fig. 5 shows comparative curves of a smaller machine, A being the curve of an original cast-steel machine with normal polar arc, and B that of a cast-iron machine with restricted polar arc, the subsidiary brush being so placed as to give a practically constant output or straight-line curve, after the maximum has been reached.

Such a machine as is herein described is specially adapted, in conjunction with accumulators, for the lighting of moving vehicles, such as motor cars, and for railway train lighting, and the like, and for a variety of other purposes in which it is necessary to compensate automatically for varying load and speed, but it is not necessarily confined to these uses.

Having now particularly described and ascertained the nature of my said invention, and in what manner the same is to be performed, I declare that while I do not claim in general the construction of a dynamo in which the polar area is entirely or almost entirely limited to the area of the cross-section of the pole core or shank, what I do claim is:—

In a dynamo, the combination with field magnets provided with field windings, an armature, main line brushes and a subsidiary brush connected with a winding of the field magnets so as to add to the force of the field magnets at low speed, the field magnet poles having their areas adjacent to the armature restricted substantially to the cross-sectional area of the pole-cores to limit the displacement of the axis of the magnetic flux, the main brushes being given a predetermined lead, and the subsidiary brush being given a sufficiently greater predetermined lead than the main brushes so that at high speed the current through the field coils connected therewith will still add to the strength of the field magnets in a diminished degree and prevent the production of reverse current in said coils at any time.

HENRY LEITNER.
